(57) **CLAIM**

The ornamental design for an antenna for wireless tag, as shown and described.

DESCRIPTION

The FIGURE is a front view of an antenna for wireless tag, showing our new design.

The broken lines in the drawings illustrate portions of the antenna for wireless tag that form no part of the claimed design. The dot-dash lines represent only the boundary between the claimed portion and unclaimed portions.

All elements of the claimed design are flat and coplanar.
